UNITED STATES PATENT OFFICE.

CHRISTIAN REICHMANN, OF PHILADELPHIA, PENNSYLVANIA.

IMPROVEMENT IN LAMP-SHADE SUPPORTERS.

Specification forming part of Letters Patent No. 40,361, dated October 20, 1863.

To all whom it may concern:

Be it known that I, CHRISTIAN REICHMANN, of Philadelphia, in the county of Philadelphia and State of Pennsylvania, have invented a new and Improved Lamp-Shade Supporter; and I do hereby declare that the following is a full, clear, and exact description of the same, reference being had to the accompanying drawings, making a part of this specification, in which—

Figure 1 is a side view of my invention after being cut out from the sheet metal, and previous to being bent; Fig. 2, a side view of the same, bent and adjusted in proper form for use; Fig. 3, a plan or top view of the same.

Similar letters of reference indicate corresponding parts in the several figures.

This invention consists in stamping or cutting the shade-supporter in one piece out of a plate of sheet metal, and in such a manner that it will be straight when first cut, and be capable of being bent in the form of a circle or band, and admit of being adjusted to the shade with the greatest facility.

The object of the invention is to economize in the construction of shade-supporters, both as regards labor and the consumption of stock, and at the same time obtain one equally as durable as any of those hitherto devised.

To enable those skilled in the art to fully understand and construct my invention, I will proceed to describe it.

A, Fig. 1, represents the supporter as it is cut from the sheet metal.

It will be seen by referring to the above figure that it is a straight strip, *a*, provided at suitable distances apart, with three projections, *a'* *a'* *a'*, at its upper edge, and three projections, *b* *b* *b*, at its lower edge. Each projection *a'* is in line with a projection, *b*, and between the projections *b* at the lower edge of the strip there are smaller or shorter projections, *c*. There are also short projections *d* between the projections *a'* at the upper edge of the strip, but these are designed simply for ornament. One end of this strip has two slots, *e* *e*, cut vertically through it, and the opposite end is formed of a narrow piece, *f*, that may be passed through the slots *e* *e*. These parts are all cut at one operation out

of a sheet of metal, rolled or spring brass being the preferable material, and it will be seen by referring to Fig. 1 that they may be cut out of a metal plate with but a small waste of stock, the red outline showing the second or adjoining cut. This is an important feature, for waste metal is only worth one-half the first cost of the stock, and in manufacturing a cheap article, like shade-supporters, this saving in the waste is a large item. This metal strip is bent or curved in the form of a circle or band, as shown in Fig. 3, the piece *f* being passed through the slots *e* *e*, as shown in Fig. 2, and the end of *f* bent so as to form a catch, *g*, to prevent *f* casually drawing out of the slots *e* *e*. The projections *a'* *b* are then bent inward in an inclined position to form springs to grasp the lamp-chimney, and the short projections *c* are bent outward to form supports for the upper end of the shade to rest upon, as will be seen by referring to Fig. 2, in which the upper part of the shade is indicated in red. The supporter is applied to the shade by contracting or diminishing the diameter of the former, as shown in red in Fig. 3, the piece *f* being shoved through the slots *e*. This admits of the supporter being readily adjusted in the orifice at the apex of the shade, and when the supporter is thus adjusted it is expanded so as to fit and bind firmly in the orifice of the shade. By this construction I can manufacture shade-supporters far cheaper than any now in use, and equally as strong and durable and capable of being applied to the shade with much greater facility.

I am aware that it is not new to stamp or cut out the springs of a lamp-shade support with a portion of the body of the same. This feature may be seen in a supporter, a patent for which was granted to William F. Shaw December 14, 1858. In this invention, however, the springs form part of a circular plate, which confines one of three pieces of which the supporter is composed. No material saving in stock is effected by this plan—only a saving in labor.

I do not claim, broadly, a lamp-shade supporter with springs all cut out of a single piece of metal, irrespective of the arrangement and construction of the parts as a whole.

I claim, therefore, as new and desire to se-

cure by Letters Patent as an improved article of manufacture—

A lamp-shade supporter with springs *a' b* and projections *c*, cut at one operation in a single piece out of sheet metal, and then bent in annular form with its ends secured by the piece *f* and slots *e e*, or other fastening, which

will admit of the expansion and contraction of the supporter, substantially as and for the purpose herein set forth.

CHRISTIAN REICHMANN.
